IMPACT TOOL FOR MAKING
POWDER HOLES

Harry H. Van Pelt, Eureka, Calif.

Application May 7, 1948, Serial No. 25,717

4 Claims. (Cl. 255—5)

1

The present invention relates to improvements in an impact tool for making a powder hole, commonly referred to as a powder iron, and its principal object is to provide a tool of the character described to facilitate the driving of a hole underneath a tree stump for accommodation of a charge of powder.

More particularly it is proposed in the present invention to provide a unitary tool in which the driven element and the drive element are combined in such a manner that the drive element is guided by the driven element and forms a relatively simple unit therewith.

It is further proposed to provide a tool of the character described in which the drive element is arranged for easy manipulation by a person of suitable height regardless of the length of the driven element projecting above the earth surface.

It is further proposed to provide a tool of the character described in which means are provided for facilitating the removal of the tool by loosening the same with respect to the earth wall and also by providing a structure in which the drive means may be used for driving the driven member in the opposite direction.

Further objects and advantages of my invention will appear as the specification proceeds, and the novel features of my invention will be fully defined in the claims attached hereto.

The preferred form of my invention is illustrated in the accompanying drawing, in which Figure 1 shows a longitudinal section through my impact tool, portions being broken away, and other portions being shown in elevation.

Figure 2, a transverse section taken along line 2—2 of Figure 1,

Figure 3, a transverse section taken along line 3—3 of Figure 1, and

Figure 4, a transverse section taken along line 4—4 of Figure 1.

While I have shown only the preferred form of my invention, I wish to have it understood that various changes and modifications may be made within the scope of the claims attached hereto without departing from the spirit of the invention.

Referring to the drawing in detail, my impact tool comprises in its principal features a tube 1, a plunger 2 slidable in the tube and a weight 3 formed integral with the plunger and projecting beyond the upper end of the tube for driving the latter into the earth surface when the weight is dropped from a raised position. The upper end of the tube has a sleeve 4 tightly fitted therein,

2

and the sleeve terminates, above the tube, in a heavy shoulder 5 bearing upon the upper end of the tube and offering a relatively large striking base 6 for the weight 3. The sleeve 4 forms a shoulder 7 on the inside of the tube, and the plunger 2 is provided with a cooperating shoulder 8 at its bottom end for striking the shoulder 7 on an upward thrust of the weight 3, for loosening the tool.

- 10 The weight 3 is cylindrical in form and has a transverse hole 9 for receiving the horizontal portion 10 of a handle. The handle turns at a relatively sharp angle to present an operating shank 11 running substantially parallel to the tube 1. 15 It will be noted that the shank 11 may be swung from the position shown in Figure 1 to a reverse position in which it projects upwardly beyond the weight.

- The plunger 2 may be locked to the tube 1 by 20 means of a pin 12 mounted upon a spring 13 secured upon the shoulder 5 by means of screws 14. The tube 1 and the plunger 2 have registering holes 15 and 16 adapted to be brought in registry and to be engaged by the pin 12 for locking 25 the tube with respect to the plunger. The pin 12 may be disengaged by merely lifting it out of the hole 16 and by turning the plunger to bring the hole 16 out of registry with the hole 15.

- The lower end of the tube is formed with a 30 solid pointed head 17, a portion 18 of which is firmly anchored in the tube. The tube has a plurality of fins 19 mounted longitudinally upon the outer surface thereof and extending preferably substantially from end to end. These fins are used to facilitate the working loose of the tool 35 upon completion of the driving operation.

- The manner of using the invention will be 40 readily understood from the foregoing description. The length of the tool is preferably between 6 and 8 feet, and it is principally intended for driving powder holes underneath a tree stump. In beginning the operation, the operator first selects a likely spot adjacent the tree stump from which the tool may be driven into the ground surface at an angle, and then sets the point 17 on 45 said spot, with the tool held at an angle directed substantially toward the axis of the tree stump. With the pin 12 disengaged, the operator then lifts the weight 3 by means of the handle shank 11 and allows the weight to drop upon the shoulder 6 for driving the tool into the ground surface. This operation is repeated until the desired depth 50 has been obtained.

- While at the beginning of the operation the 55 tool may extend some 6 or 8 feet above the ground

surface and it is convenient to operate the weight with the shank handle in a downwardly projecting position, when the tool is about 3 or 4 feet down the operator will find it more convenient to turn the handle shank 11 through an angle of about 180° which will bring it again to convenient height for the operator to manipulate.

After the tool has been driven to the desired depth the next problem is to remove the same. This task is greatly facilitated by the provision of the pin 12 for locking the tube to the plunger and by the provision of the outside fins. After the pin 12 has been engaged the operator merely turns the weight back and forth by suitable operation of the handle 11 thus causing the fins 19 to work against the earth wall surrounding the tool and loosening the latter. After the tool has thus been loosened it will be comparatively easy to remove the same, but if it is still hard to start the removal movements the operator may readily initiate such movements by thrusting the weight 3 upward by means of the handle shank 11 which will cause the plunger head 8 to impinge upon the shoulder 7 for driving the tool in an upward direction.

The hole 9 for accommodating the horizontal portion 10 of the handle may be shaped in such a manner as to allow the bent portion of the handle to be pulled therethrough and to bring the shank 11 in horizontal position which would somewhat facilitate the turning movement.

I claim:

1. An impact tool for making a powder hole, comprising a tube having a lower end adapted for driving into the ground surface, a plunger within the tube for driving the same and having a weight on its upper end outside the tube, a handle projecting sidewise from the weight, fins arranged lengthwise upon the outside of the tube to permit the tube to be loosened with respect to the earth wall when the tube is turned in a back and forth movement, the plunger being normally revolvable in the tube and having a recess in the side thereof, and the tube having a spring-actuated pin slidable in the wall thereof and engageable in the recess for interlocking the tube and the plunger to allow the former to be turned by operation of the plunger handle.

2. An impact tool for making a powder hole, comprising a tube having a lower end adapted for driving into the ground surface, a sleeve tightly fitted in the upper end of the tube and having a shoulder bearing on the outer end of the tube, a plunger slidable within the tube and having a weight at its outer end for driving the

tube when the weight strikes the shoulder, a handle projecting sidewise from the weight, fins arranged lengthwise upon the outside of the tube to permit the tube to be loosened with respect to the earth wall when the tube is turned, the plunger being normally revolvable in the tube and having a recess in the side thereof, and a leaf spring mounted upon the outer face of the shoulder and having a pin projecting through the wall of the tube so as to bear on the plunger, the pin being engageable in the recess when brought into registry therewith for interlocking the tube and the plunger to cause the sleeve to turn with the plunger when the latter is turned by means of its handle.

2. An impact tool for making a powder hole, comprising a tube having a lower end adapted for driving into the ground surface, a sleeve tightly fitted in the upper end of the tube and having a shoulder bearing on the outer end of the tube, a plunger slidable within the tube, a weight on the outer end of the plunger and adapted to strike the shoulder for driving the tube into the ground surface, and a plunger head on the inner end of the plunger and adapted to strike the sleeve for driving the tube out of the ground surface.

3. An impact tool for making a powder hole, comprising a tube having a lower end adapted for driving into the ground surface, a sleeve tightly fitted in the upper end of the tube and having a shoulder bearing on the outer end of the tube, a plunger slidable within the tube, a weight on the outer end of the plunger and adapted to strike the shoulder for driving the tube into the ground surface, and a plunger head on the inner end of the plunger and adapted to strike the sleeve for driving the tube out of the ground surface, the shoulder having means mounted thereon for interlocking the tube and the plunger.
